TOWEL RACK

Ann Sink, 218 Lowell Ave., Palo Alto, Calif. 94301

Filed Apr. 26, 1973, Ser. No. 354,766

Term of patent 14 years

Int. Cl. D6—06

U.S. CL. D6—100

FIG. 1.

FIG. 2.

FIG. 3.

FIG. 5.

FIG. 4.

FIG. 1 is a perspective view of a towel rack showing my new design;

FIG. 2 is a top plan view thereof;

FIG. 3 is a side elevational view thereof;

FIG. 4 is a bottom plan view thereof; and

FIG. 5 is an other perspective view thereof, with the towel holding arms removed for convenience of illustration.

I claim:

The ornamental design for a towel rack, as shown.
